TUNABLE CAVITY RESONATOR
MAGNETRON

John S. Donal, Jr., Princeton, N. J., Barremore B. Brown, Lancaster, Pa., and Carmen L. Cuccia, Princeton, N. J., assignors to Radio Corporation of America, a corporation of Delaware

Application August 13, 1947, Serial No. 768,362

5 Claims. (Cl. 250—27.5.)

1

This invention relates to electron discharge devices and more particularly to magnetrons incorporating cavity resonators and means for adjusting the frequency response thereof.

In devices operating at very high frequencies the reactive elements consist generally of closed structures in which the physical shape and configuration determine the operating frequency. In generating oscillations at very high frequencies, namely, in the micro-wave spectrum, discharge devices incorporate in their electrode structure cavity resonators in various forms which have a fixed frequency characteristic determined chiefly by their physical dimensions.

Resonators used in discharge devices, for example, in magnetrons, may have various forms and comprise generally slots or sectors machined into a solid block which functions as the anode electrode. The resonators are so arranged as to surround the cathode electrode and the assembly is placed in an evacuated envelope. In certain structures the anode containing the resonators serves also as the housing and may be evacuated.

In view of the fact that resonators are solid bodies and their resonance is determined by their geometry, it is difficult to change the resonant frequency of a completed structure. Small variations in mass production are unavoidable which result in slightly different frequency characteristics in devices intended to operate at a particular frequency. For this and for other reasons, it is desirable to develop means for tuning resonators of the cavity type, particularly in discharge devices where such resonators are inaccessible in a hermetically sealed structure.

Although cavity resonators have distributed reactances, certain shapes used in magnetron oscillators exhibit some lumping of the capacitive and inductive branches. Consequently, the frequency determining parameters of the resonators may be varied if the reactance of one or both of these branches is altered. Various schemes have been devised in the art to alter the inductance or the capacitance of cavity resonators. Some of these schemes have been complicated and difficult to incorporate in practical embodiments. Others proved ineffective for a desired range of frequency change. In view of the mechanical difficulties, tuning arrangements involving the change of the inductance of the resonator heretofore developed are directed to altering the effective inductance of only one resonator. This causes in some cases non-uniformity in operation. Tuning arrangements which simultaneously alter all resonators

2

confine the change to the capacitance which is mechanically easier to obtain.

The present invention has for its main object to improve upon the tuning arrangements of cavity resonators providing means for altering simultaneously the effective inductance of all the resonators in the assembly.

Another object of the invention is to provide means for tuning a magnetron oscillator which may easily be incorporated in the structure and actuated externally.

A particular feature of the invention is that tuning of a magnetron oscillator may be accomplished over a wider range and in smaller increments of movement of the tuning mechanism.

Another feature of the invention is that the tuning mechanism in accordance therewith, while flexible in operation, maintains the setting after adjustment.

20 Other objects and features will be apparent from the following description of the invention pointed out in particularity in the appended claims and taken in connection with the accompanying drawing in which—

25 Fig. 1 is a front elevational view, partly in cross-section, of a magnetron incorporating the tuning mechanism;

Fig. 2 is a top view taken along line 2—2 of Fig. 1; and

30 Fig. 3 is a side elevational view with the housing partly cut away to show the entire assembly.

Referring to the figures, a particular type of magnetron is shown to illustrate the application of the invention. The various components comprising the tuning device are particularly well suited for the type of construction shown. It will be seen that the principles involved may be applied to all types of magnetrons or other discharge devices in which cavity resonators are so arranged 40 as to be symmetrically disposed and intercoupled.

The magnetron comprises essentially an anode element 4 which is in the form of a metallic block having a central aperture 5 along the axis of which is mounted a cathode electrode 6. Radially 45 extending toward the cathode 6 and surrounding it within the aperture 5 are a number of vanes 7 forming resonators 7', each in the shape of sector of a circle. The resonators 7' are open in the direction transverse to the anode 4 and terminate in the wall of the anode aperture 5 in the direction radial to the cathode. Since the resonators 7' are open at both sides of the anode 4, there is an electro-magnetic intercoupling between the resonators. The magnetic lines of force of the 55 radio frequency field are bunched generally to

ward the closed end walls of the resonators whereas the capacitive component of the field is distributed near the ends facing the cathode electrode. The capacitive portions of the resonators are also tied together by means of straps 8 and 8'.

The structure above described is used in many multi-cavity type magnetrons. No detailed illustration is believed necessary of these structural features inasmuch as the invention herein described pertains to the tuning mechanism which is adaptable to magnetrons of all types having the basic construction outlined.

Adjacent the anode 4 there is supported a conducting plate 9 provided with a circular opening of such diameter that, when concentrically aligned with the resonators, it covers a substantial portion of each resonator near the closed end wall thereof. In other words, the conducting plate adjacent the resonators forms a conductive shield over the predominantly inductive portion of each resonator. The plate 9 is hinged at one end to the anode by means of hinge elements 10 and is attached at the other end to a collar 12 on a rod 13 which extends through the envelope header 14 and terminates in a bushing 15. The plate 9 is also provided with apertures to admit the insulating bushings 16 and 17 which hold the assembly for the cathode and the magnetic inserts 18 in place supported by the anode 4. The latter is supported on the header 14 in a conventional manner. An envelope cover 14' is secured vacuum tight to the header 14 at its periphery.

The bushing 15 is secured to the header or base 14 by means of a flexible bellows-type housing 19 which permits movement of the rod 13 with respect to the base 14 without disturbing the sealing of the inside structure and the evacuation of the envelope 20. Movement of the rod in the direction toward the anode 4 or away from it is effected by means of a differential screw 21 which is supported in a block 22 attached to the base 14. The head 23 of the screw 21 is threaded in the block 22 and the threaded portion 24 of the screw 21 is similarly engaged with the block 15, as shown in Fig. 3. This type of construction permits a vernier adjustment whereby several turns of the head 23 result in small increments of movement of the screw 21.

Other elements of the magnetron not shown in detail consist of the output coupling loop brought out through a coaxial line 26 provided with a seal 27. Similarly, the filament heating conductors of the cathode are brought out to the tubular shield 28 provided with a seal 29.

The operation of the tuning device herein described is based on the change of intercoupling between the resonators in that an obstruction is placed to the magnetic lines of force connecting adjacent resonators. As pointed out above the magnetic lines representing the inductive portion of the resonators, that is, the inductance, are predominantly near the end wall in each resonator. A conductive ring adjacent the peripheral edges of each resonator will therefore disturb the magnetic circuit. The plate 9 by its properly dimensioned aperture places a conductive shield near the peripheral edge of each resonator simultaneously and in its manner changes the effective inductance of the entire resonator structure. The nearer the plate 9 is to the anode 4, the greater is the shielding effect produced, resulting in a greater change of effective inductance. The movement of the plate 9 is effected in a simple

manner by displacing the rod 13 with respect to the base or header 14. In certain smaller magnetron structures the flexibility of the base 14, which is only a thin metal plate, is sufficient to allow the slight motion required to actuate the plate 9. In such cases the bellows type housing 19 may be entirely omitted and the rod 13 may be welded directly to the base 14. However, in larger constructions it is preferable to rely on the additional flexibility which the housing 19 provides. In a practical embodiment it was found that this tuning arrangement enabled a frequency change amounting to three percent of the operating frequency without significant decrease in tube performance.

While we have indicated the preferred embodiments of our invention of which we are now aware and have also indicated only one specific application for which our invention may be employed, it will be apparent that our invention is by no means limited to the exact forms illustrated or the use indicated, but that many variations may be made in the particular structure used and the purpose for which it is employed without departing from the scope of our invention as set forth in the appended claims.

We claim:

1. An electron discharge device including an anode electrode having a plurality of anode segments defining a central space and a plurality of radially extending cavity resonators surrounding said space, a cathode electrode adjacent said anode electrode for supplying electrons to said central space, an envelope enclosing said electrodes, means for changing the electrical characteristics of said resonators comprising a tuning element, hinge means mounting said tuning element on said anode electrode for pivotal movement of said tuning element relative to said resonators, actuating means independent of said hinge means connected to said tuning element within said envelope and extending therefrom, and adjustable means attached to said device and said element for moving said element.

2. An electron discharge device comprising a cathode electrode, an anode electrode surrounding said cathode electrode having a plurality of cavity resonators, an evacuated housing enclosing said electrodes, means for changing the electrical characteristics of said resonators comprising a tuning element adjacent said anode, hinge means mounting one end of said tuning element on said anode element for pivotal movement of said tuning element toward and away from said resonators, actuating means connected to the other end of said tuning element within said housing and extending therefrom, and adjustable means attached to said device and said actuating means for moving said actuating means.

3. An electron discharge device comprising a cathode electrode, an anode electrode surrounding said cathode electrode and having a plurality of intercoupled cavity resonators radially extending from said cathode, an envelope enclosing said electrodes, means for changing the electrical characteristics of said resonators comprising a tuning element controlling said intercoupling adjacent said anode, hinge means mounting said tuning element on said anode electrode for pivotal movement of said tuning element relative to said resonators, actuating means independent of said hinge means connected to said tuning element within said envelope and extending therefrom, and adjustable means attached to said de-

vice and said actuating means for moving said actuating means.

vice and said actuating means for moving said actuating means.

4. An electron discharge device comprising a cathode electrode, an anode electrode surrounding said cathode electrode and having a plurality of intercoupled cavity resonators radially extending from said cathode each forming a sector of a circle and terminating at the periphery thereof, an evacuated envelope enclosing said electrodes, means for changing the electrical characteristics of said resonators comprising a tuning element adjacent said anode, hinge means mounting one end of said tuning element on said anode element for pivotal movement of said tuning element toward and away from said resonators to change the effective peripheral termination of said resonators simultaneously in a degree varying with the distance of said tuning element from said anode, adjustable actuating means for said tuning element within said envelope and extending therefrom, and means attached to said device and said actuating means for moving said actuating means.

5. An electron discharge device including an anode electrode having a plurality of inter-coupled cavity resonators, a cathode adjacent said anode electrode for supplying electrons to said anode electrode, an evacuated envelope enclosing said electrode and said cathode, means for changing the electrical characteristics of said

resonators and including a tuning element adjacent one end of said anode electrode and movable toward and from said resonators, said tuning element including a plate element hingedly mounted at one end to said anode electrode, an actuating member rigidly connected to the other end of said tuning element and extending from said envelope, and adjustable means for adjusting said actuating member for pivoting said tuning element toward and from said anode electrode for tuning said device comprising a block attached to said member, a second block attached to said envelope and a differential screw threaded into said blocks.
